(57) CLAIM

The ornamental design for a cooking appliance, as shown and described.

DESCRIPTION

FIG. 1 is a perspective view of a cooking appliance showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines are for environmental purposes only and do not form any part of the claimed design. The oblique shading lines indicate transparent or translucent portions of the cooking appliance.

1 Claim, 5 Drawing Sheets
